UNITED STATES PATENT OFFICE

133,619

DESIGN FOR A BLOCK PUZZLE OR SIMILAR ARTICLE

James R. O'Neil, San Francisco, Calif.

Application May 19, 1942, Serial No. 106,949

Term of patent 3½ years

To all whom it may concern:

Be it known that I, James R. O'Neil, a citizen of the United States of America, residing in the city and county of San Francisco, State of California, have invented a new, original, and ornamental Design for a Block Puzzle or Similar Article, of which the following is a specification, reference being had to the accompanying drawing, forming part thereof.

Fig. 1 is a plan view of a block puzzle, showing my new design;

Fig. 2 is a plan view of one of the blocks shown in Fig. 1 separated from the container; and

Fig. 3 is a side elevational view of the block shown in Fig. 2.

I claim:

The ornamental design for a block puzzle or similar article, as shown.

JAMES R. O'NEIL.
